Fig. 2

UNITED STATES PATENT OFFICE

GEORGE W. DUNHAM, OF UTICA, NEW YORK, ASSIGNOR TO THE WHIRLDY CORPORATION, OF UTICA, NEW YORK, A CORPORATION OF NEW YORK

SEDIMENT-DISPOSING ARRANGEMENT FOR LAUNDRY MACHINES

Application filed January 11, 1926. Serial No. 80,490.

This invention relates to sediment disposing arrangements for laundry machines, and more particularly, to such an arrangement for use in a machine in which the receptacle for holding the soiled articles is of the imperforate type.

In laundry machines having receptacles of the imperforate type the receptacle may be made with sufficient portions of the walls imperforate so that the receptacle may hold both the soiled articles and the washing liquid for washing the same during the washing period. A suitable agitating arrangement may be provided to agitate the soiled articles for washing. In this type of machine the receptacle with the soiled articles and liquid therein may be rotated at high speed to discharge the liquid during centrifugal drying operations.

In this type of receptacle the walls being substantially imperforate, during the drying period the liquid will be thrown to the outer walls over which it will climb and be thrown clear of the receptacle. A suitable tank may be provided to contain the receptacle and to hold the excess washing liquid and to catch the same during centrifugal drying operations. During the washing period the washing liquid may be pumped from the bottom of the tank into the top of the receptacle continuously to replace the liquid which is kicked or splashed out of the receptacle by the washing action and also to discard the scum and to provide an improved washing action. This type of machine is described at length in co-pending application, Serial No. 18,086, filed March 25, 1925.

According to the invention, in order to discard sediment which settles to the lowest point of the receptacle during washing operations small holes may be provided at the lowest point of the receptacle to dispose of the sediment. The amount of washing liquid which is lost through these holes may be so small compared to the amount of liquid

continuously supplied to the top of the receptacle as to be almost negligible.

Various other objects and advantages of the invention will be obvious from the following particular description of one form of device embodying the invention or from an inspection of the accompanying drawings; and the invention also consists in certain new and novel features of construction and combinations of parts hereinafter set forth and claimed.

In the drawings accompanying and forming part of this specification, a practical commercial embodiment of the invention is disclosed, but as such illustration is primarily for purposes of disclosure, it will be understood that the structure may be modified in various respects without departure from the broad spirit and scope of the invention as hereinafter defined and claimed.

Fig. 1 is an elevational view of a laundry machine with a sediment disposing arrangement according to the invention, parts of the machine being broken away to more clearly show the structure thereof; and

Fig. 2 is a fragmentary view of the bottom of the receptacle showing the sediment disposing holes.

In the following description and in the claim parts will be identified by specific names for convenience, but they are intended to be as generic in their application to similar parts as the art will permit.

Referring now to the drawing, the particular laundry machine illustrated may comprise a tank 1 supported by suitable legs 2. Cooperating with the tank may be a hollow supporting column assembly which may comprise a supporting column 3 having a receptacle 4 journaled at the top of the same and having a suitable pump 5 and gearing disposed in a gear box 6 at the bottom of the same.

The receptacle 4 which is of the imperforate type may comprise an annular up-

standing wall 7 flaring slightly upwardly and a tubular upstanding hub 8 concentric therewith. A bottom wall 9 may be provided formed integral with the side wall 7, 5 the bottom wall having formed therein an annular trough 10 and extending over into secure engagement with the tubular hub 8. In order to provide additional reenforcing of the receptacle a reenforcing plate 11 may 10 be provided extending from the bottom of the trough 10 to the hub 8 and fastened securely thereto.

The bottom of the trough may have a plurality of sediment disposing holes 15 therein 15 through which the sediment may be discharged from the receptacle in the manner hereinafter pointed out more in detail. The holes 15 may be so arranged that the amount of liquid lost through them is inappreciable 20 when compared with the liquid continuously supplied by the discharge nozzle 19.

At the top of the receptacle an upwardly and inwardly extending guard ring 13 may be secured to the side wall 7 by means of a lap 25 joint or any other suitable means. A plurality of overflow or discharge holes 14 may be provided through the lap joint to allow the liquid to be discharged from the receptacle during drying operations. The function of 30 the guard ring is to prevent the loss of the articles which are being washed during the washing period and also during the drying period. A stand pipe or riser 16 may be provided at the side of the tank 1 having at the 35 bottom thereof a trap or sump 17 and having a connection 18 with the discharge of the pump 5. The upper end of the riser 16 may end in a swingable discharge nozzle 19 which may be arranged to discharge selectively into 40 the receptacle 4, into the tank 1 or clear of the tank.

In order to agitate the articles which are to be washed a suitable agitator may be provided which may consist of paddles or blades 45 21 so shaped as to effectively and thoroughly agitate the washing liquid and the soiled articles without destructive effects thereon.

It will be understood that suitable driving mechanism may be provided for imparting 50 a rotary oscillatory motion to the agitator during the washing period and for rotating the receptacle 4 during the drying period, the power necessary for accomplishing these results being supplied by a motor 22 suspended 55 from the bottom of the tank 1. The motor operates through suitable gearing which forms no part of this invention, having been covered in co-pending application, Serial No. 30,759, filed May 16, 1925. It will be understood that 60 during the drying period the agitator may be removed from the machine by a suitable clutch connection. During the washing period the agitator may be given the rotary oscillatory motion above referred to, and the 65 pump 5 set in operation to pump washing liq-

uid from the bottom of the tank 1 through the riser 16 into the top of the receptacle 4. During the washing operation the washing liquid will be kicked and splashed out through the discharge holes by the agitator and also 70 will flow through the sediment disposing holes 15. It will be understood, however, that the amount lost through the sediment disposing holes may be made almost negligible compared to the amount continuously supplied by the riser pipe 16. 75

As the agitator functions during washing operations the heavy sand and other dirt which tends to settle will eventually settle to the bottom of the trough 10 whence, due to the 80 oscillatory movements of the soiled articles and washing liquid, it will be pushed through the sediment disposing holes 15, whence it will fall to the bottom of the tank 1. The liquid in the bottom of the tank is comparatively quiet and most of the sediment will remain there where it can do no harm. If any sediment should be sucked into the pump 5 and discharged therefrom a good part may 85 lodge in the trap or sump 17 and the very small part, if any, which may be carried up the riser 16 to be discharged back into the receptacle 4 will eventually work its way to the sediment disposing holes 15.

The centrifugal drying will be accomplished by the suitable gearing above referred to, the water being discharged through the discharge openings 14 as is well known in the art, the discharge of liquid through the discharge nozzle 19 being stopped during this 100 period.

It will be appreciated that the provision of holes in the bottom of the imperforate type receptacle 4 does not interfere in any way with the ability of the receptacle to effectively hold washing liquid for washing purposes and yet it allows the sediment to be effectively disposed. This arrangement is made possible by the continuous circulation of washing liquid which is sufficient to cause it to be continually discharged through the overflow holes 14. 105

In this application the term imperforate type as applied to the receptacle is intended to include any type of receptacle which is 110 sufficiently imperforate to hold laundry liquid for washing or other purposes, regardless of the fact that holes may be provided for certain purposes.

While I have shown and described and have 115 pointed out in the annexed claim certain novel features of the invention, it will be understood that various omissions, substitutions and changes in the forms and details of the device illustrated and in its operation may be 120 made by those skilled in the art without departing from the spirit of the invention.

Having described my invention, I claim:

In a laundry machine, a tank, a receptacle 125 mounted therein, said receptacle being adapt-

ed to hold articles to be treated and having sufficient portions of its walls imperforate to hold washing liquid, an agitator for agitating the liquid and articles, said receptacle having sediment disposing holes and means for continuously supplying said receptacle with washing liquid during washing operations.

In testimony whereof I have hereunto set
10 my hand.

GEORGE W. DUNHAM.
